RELASTING MACHINE

Angelo Perri, Groveland, Mass., assignor to Allied Shoe Machinery Corp., Haverhill, Mass., a corporation of Massachusetts

Application January 13, 1945, Serial No. 572,620

11 Claims. (Cl. 12—15)

1

This invention relates to mechanism for inserting lasts in shoes. More particularly it relates to a machine for inserting a last in a shoe which previously has been lasted and which has been removed from the last on which it was lasted.

Frequently it is necessary or desirable to remove from its last a shoe in process of manufacture after its upper has been lasted and subsequently to re-insert a last therein preparatory to performing some later operation thereon, such as applying the heel, for example. Although conventional lasts have their fore and aft sections hinged together so that a last may be broken at its hinge to facilitate its insertion in and removal from a shoe, it is difficult to re-insert a last in a previously lasted shoe because the lasting operation necessarily conforms the shoe upper precisely to the last curvatures and, having removed the last, its re-insertion involves forcing it into a cavity which, due to some resiliency in the lasted upper material, usually is smaller than the last. In any event the fit is so tight that considerable force is required to get a last back into a shoe subsequent to a removal of the last upon which the shoe initially was formed.

It is an object of my present invention to provide mechanism for quickly and effectively re-inserting a last in an already lasted shoe. I provide a low cost treadle operated press in which a plunger is spring-actuated in response to depression of a treadle to forcibly engage the rear portion of a lasted shoe whose forepart has been placed on a last while the latter is broken at its hinge. The last is unyieldingly supported in the past of the plunger, and the stroke of the plunger forces the rear portion of the shoe over the last and simultaneously snaps the last to its extended condition.

Another object is to provide means for resetting the plunger against the resilience of its actuating springs. According to the invention, depression of a treadle after a shoe has been relasted elevates the last with the shoe thereon to force the plunger upward until a latch engages and maintains the plunger in elevated set condition ready for another re-lasting work stroke.

A further feature resides in the provision of a shoe horn facilitating movement of the rear portion of a shoe onto a last in response to a stroke of the plunger, and the shoe horn conveniently is withdrawn from the re-lasted shoe during the operation of re-setting the plunger.

Still another object is to provide for re-lasting shoes having only a strap extending around the rear part of the upper. A notched strap-engag-

2

ing member is removably and yieldingly carried on the plunger for forcing the strap over the last as the plunger descends, the strap-engaging member conveniently and effectively being supported between coacting springs of the plunger.

It is, moreover, my purpose and object generally to improve upon prior re-lasting machines and mechanisms.

In the accompanying drawings:

10 Figure 1 is a top plan view of a re-lasting machine embodying features of my invention;

Figure 2 is an elevation of the upper part of the machine of Figure 1, looking in the direction of the arrows on line 2—2 of Figure 1;

15 Figure 3 is a cross-sectional view of the lower part of the machine of Figure 1, on line 3—3 of Figure 1;

Figure 4 is a fragmentary elevation illustrating the plunger after it has descended into engagement with a shoe, and showing the last extended and the shoe re-lasted;

20 Figure 5 is a view similar to Figure 4 but with the last elevated to reset the plunger;

Figure 6 is a fragmentary elevation showing 25 a strap type upper re-lasted with the aid of a depending strap-engaging member which is shown in dotted outline in Figure 2;

Figure 7 is a rear face view of the shoe horn and its supporting levers; and

30 Figure 8 is a perspective of the bell crank lever for operating the latch releasing plate.

Referring to the drawings, the embodiment of my invention as therein represented, has a base 10 from which rises the vertical hollow standard 12. Carried at the upper end of standard 12 is the horizontally disposed plate 13 which conveniently may have secured thereto in any suitable manner the work table sections 14.

35 A last supporting shaft 16 extends vertically and slidably within standard 12 and upward through plate 13 to a substantial height above the work table, its upper end being reduced as at 18 for engaging in the usual socket of a last 20, for mounting the last on the shaft 16. The lower end of shaft 16 is connected by link 22 to one end of a treadle lever 24 which is pivoted at

40 26 intermediate its ends on bracket 28 suitably secured on base 10. Standard 12 has an opening 30 in its wall through which the treadle lever 45 extends so that the forward pedal end 25 of the lever is in position to be conveniently engaged and depressed by the foot of an operator.

Secured above and to the table 14 is the yoke indicated generally at 32 which has the lower 50 bearing portion 34, through which the shaft 16

slidably extends, and the vertically aligned upper bearing portion 36 wherein is slidably mounted the plunger shaft 38 having the head 40 secured to its lower end. Shaft 38 has a keyway 42 therein in which set screw 44 in bearing portion 36 engages, to prevent rotation of the shaft while permitting vertical movements thereof. A collar 46 is slidably keyed on plunger shaft 38 with a relatively heavy coil spring 48 on the shaft and engaging between the fixed bearing portion 36 of yoke 32 and the upper side of collar 46. A relatively weaker coil spring 50 on shaft 38 engages between the lower side of collar 46 and the plunger head 40.

The upper end of plunger shaft 38 has adjustably threaded thereon a finger nut 52 which may be adjusted along the threaded upper end of plunger shaft 38 to vary the stroke of the plunger which normally is held elevated by the latch lever 54. As represented, the latch lever 54 is pivotally suspended from a collar 56 which is in turn suspended from the finger nut 52 by means of hook elements 58 loosely engaging in groove 60 of the finger nut. Collar 56 is slidably engaged around shaft 38 and is held against rotation thereon by a set screw 62 engaging in keyway 42 of the shaft. Fig. 2 shows latch 54 engaged with the bearing portion 36 and acting as a strut maintaining plunger 38, 40 in elevated position against the resiliency of both springs 48, 50. When the latch is disengaged, by means to be described, the plunger is snapped downward into forcible engagement with a shoe on last 20, as shown in Fig. 4.

The means for disengaging latch 54 comprises a forked plate 64 whose forked end rests on the top of bearing portion 36 of yoke 32, straddling shaft 38, and whose other end is pivotally connected at 66 to the long arm 68 of bell crank lever 70 which is pivotally mounted at 72 on yoke 32. The shorter arm 74 of the bell crank lever has a pin 76 projecting therefrom at one side, under which engages the upper end of an actuating arm 78 which is carried on the actuating shaft 80, whose lower end is connected to a second treadle lever 82 pivotally mounted at a mid-location along it at the pivot 26. The forwardly projecting pedal part 83 of this treadle is elevated a little above the pedal 25 as shown in Fig. 3, and overlies it a little as shown in Fig. 1.

Referring to Fig. 2, it will be seen that the actuating arm 78 is indirectly supported on actuating shaft 80 by being pivotally mounted at 84 on one of a spaced pair of links 86, 88 which are pivotally connected at 90, 92 to the head piece 94 on the upper end of actuating shaft 80. A short link 96 connects the upper ends of these links and has a lower edge 98 for engaging from above the pin 76 which projects between the spaced links 86, 88 and which is engaged from below by the upper end of actuating arm 78 as previously described. The pivoted lower end of the actuating arm has a projecting foot 100 thereon; and head piece 94 has the chambered boss 102 for seating one end of a coil spring 104 whose other end bears against foot 100 tending to rotate actuating arm 78 clockwise and thus tending to maintain its upper end, which has slightly inclined curvature as at 79, pressed against pin 76. A set screw 106 permits adjustment of the tension of spring 104. This link construction at the upper end of actuating shaft 80 provides flexibility in its connection with pin 76.

It will be obvious that, with the construction shown and described, an upward movement of

actuating shaft 80 and the carried actuating arm 78 will cause counter-clockwise movement of bell crank 70 with an accompanying movement of plate 64 to the left in Fig. 2. Upon a predetermined movement of plate 64 a pair of projecting pins 108 on latch 54 are engaged and the latch swung to unlatched position, immediately upon which the springs 48, 50 snap the plunger 38, 40 downward into forcible engagement with a shoe on last 20, as seen in Fig. 4.

As herein shown, the plate 64 has a pair of arms 110, 112 pivotally mounted on its top side as at 114, 116, with a spring 118 urging the arms together. However, a vertically projecting part 120 of the plate intervenes between the arms adjacent their pivots and limits their movement toward each other so that they normally extend in spaced parallelism as seen in Fig. 1. When the plate 64 moves to the left, as previously described, it is the ends of arms 110, 112 that engage the latch pins 108 and, after the plunger has descended, the arms, on the return stroke of plate 64, can yield to get past the part 56 on shaft 38 which will have dropped between them. It should be understood, however, that the plate 64 itself may be so shaped that it directly may engage and release the latch 54.

The tight fit of a pre-lasted shoe which is to be relasted requires a shoe horn to get the rear part of the shoe on the last. I provide a suitable shoe horn 122 pivoted at 124 at the upper ends of a pair of links 126 whose lower ends are pivoted at 128 on the yoke 32. The horn has a counter-weight 130 thereon tending to swing the horn clockwise about its pivot 124 and, in conjunction with the weight of the horn and the links 126, tending to rotate the links clockwise about their pivot 128. A stop 132 on the yoke 32 constitutes an abutment against which counter-weight 130 engages upon gravitational clockwise swinging thereof when the horn is disengaged from a shoe. The horn is adapted for manual engagement in a shoe between the back of the shoe and the last 20 preliminarily to operation of the plunger for forcing a shoe onto the last.

In the operation of my improved re-lasting machine, the operator stands at the front of the machine as seen in plan in Fig. 1, beside the pedals 25, 83. He or she, with the right hand, places a last 20, broken at its hinge and having a shoe on its forepart, on the reduced upper end 18 of shaft 16. With the left hand, the shoe horn 122 may be inserted in place, as indicated in Fig. 2. During this operation of inserting a last, the plunger 38, 40 will be in the elevated position of Fig. 2, held up by the latch 54.

The operator next depresses pedal 85 which elevates actuating shaft 80 and actuating arm 78 thereby rotating bell crank lever 70 counter-clockwise and sliding plate 64 to the left in Fig. 2 until the arms 110, 112 engage the latch pins 76 and disengage the latch, to cause downward snap movement of plunger 38, 40 by the springs 48, 50. The forcible impingement of plunger head 40 against the rear part of the shoe forces it down the shoe horn 122 and snaps the last to extended position. A further depression of pedal 83 engages pedal 25 so that the latter is depressed to elevate the last with the shoe thereon thereby to cause withdrawal of the shoe horn.

During this elevation of the last 20, the incidental further upward travel of actuating shaft 80 causes the end of actuating arm 78 to ride off the pin 76; the arm swinging a little counter-

clockwise against the resilience of spring 104. Hence, the plate 64 and its arms 110, 112 are freed for return to the right in Fig. 2. Also, as the last 20 is elevated, the plunger 38, 40 is forced upward against the resilience of springs 48, 50 and the latch 54 ultimately drops by gravity into latching engagement with upper bearing part 36 of the yoke 32, to re-set the device for a similar procedure on the next shoe.

When the pedal 83 is released, the shafts 16 and 80, with their carried parts, drop by gravity back to their positions of Fig. 2, the shoe horn 122 having meanwhile dropped by gravity to its dotted position of Fig. 2. The last with a shoe thereon may then be removed and another inserted to receive similar treatment.

It is a feature of the invention that provision is made for re-lasting shoes of the open back type which have only a strap part for engaging around the back of a foot. Such a shoe is represented on a last in Fig. 6, with its rear strap part 134 engaged over the shoe horn 122. The getting of this strap part 134 to proper position on a last in the re-lasting of a shoe presents a considerable problem. According to my invention, a finger 136 may be removably pivoted at 138 on the collar 46 which is between the two plunger springs 48, 50. When so mounted, it depends by gravity and has a shoulder adapted to engage the strap part 134 to force the strap over the shoe horn and the last as the plunger 38, 40 snaps downward on its working stroke. As the last is elevated for resetting the plunger, as previously described, the shoe horn is withdrawn as in the previously described case, the finger 136 yielding as may be necessary so as not to interfere with movements of the parts.

It will be obvious from the foregoing description that I have provided a relatively low cost re-lasting machine which is extremely efficient and effective and which requires a minimum of skill to operate.

I claim as my invention:

1. A re-lasting machine comprising a support for a last, a plunger mounted for movement between an inactive position and a position in which it engages a shoe partially engaged over a last on said support, means biasing the plunger to its said shoe-engaging position, latch means for releasably holding the plunger in its said inactive position, means for releasing said latch means thereby to cause a single forcible snap movement of the plunger to its said shoe-engaging position for completing the engagement of the shoe over the last, and means for moving the last support in opposition to the said spring means biasing the plunger thereby to restore the plunger to its said inactive position.

2. A re-lasting machine comprising a support for a last, a plunger mounted for movement between an inactive position and a position in which it engages a shoe partially engaged over a last on said support, means biasing the plunger to its said shoe-engaging position, releasable means for holding the plunger in its said inactive position against the said bias, treadle-actuated means for releasing said holding means thereby to cause a single forcible snap movement of the plunger to its said shoe-engaging position for completing the engagement of the shoe over the last, and treadle-actuated means for moving the last support in opposition to the said plunger biasing means for restoring the plunger to its said inactive position.

3. A re-lasting machine comprising a support

for a last, a plunger mounted for movement between an inactive position and a position in which it engages a shoe partially engaged over a last on said support, means biasing the plunger to its said shoe-engaging position, releasable means for holding the plunger in its said inactive position against the said bias, treadle-actuated means for releasing said holding means thereby to cause forcible snap movement of the plunger to its said shoe-engaging position for completing the engagement of the shoe over the last, and means for elevating said support for a last against the said bias of the plunger to restore the plunger to its said inactive position.

10 4. A re-lasting machine comprising a support for a last, a plunger mounted for movement between an inactive position and a position in which it engages a shoe partially engaged over a last on said support, means biasing the plunger to its said shoe-engaging position, releasable means for holding the plunger in its said inactive position against the said bias, treadle-actuated means for releasing said holding means thereby to cause forcible snap movement of the plunger to its said shoe-engaging position for completing the engagement of the shoe over the last, and means for elevating said support for a last against the said bias of the plunger to restore the plunger to its said inactive position.

15 5. A re-lasting machine comprising a support for a last, a plunger mounted for movement between an inactive position and a position in which it engages a shoe partially engaged over a last on said support, means biasing the plunger to its said shoe-engaging position, a latch movable by gravity into position to latch the plunger in its said inactive position, a latch-actuating plate, and means for moving said plate into releasing engagement with said latch, thereby to cause forcible snap movement of the plunger from its inactive to its shoe-engaging position for completing the engagement of the shoe over the last.

20 6. A re-lasting machine comprising a support for a last, a plunger mounted for movement between an inactive position and a position in which it engages a shoe partially engaged over a last on said support, means biasing the plunger to its said shoe-engaging position, releasable means for holding the plunger in its said inactive position against the said bias, a plate slidably mounted adjacent said holding means and movable into releasing engagement with said holding means, a pivoted lever operatively connected to said plate, a treadle, and connections between said lever and said treadle whereby said holding means is releasable by depression of the treadle for driving the shoe into completely engaged condition over the last.

25 7. In a re-lasting machine having a support for a last and a plunger operable to and from a position where it engages a shoe partially engaged over a last on said support for completing the engagement of the shoe over the last, the combination therewith of a shoe horn insertible between the rear part of a shoe and the last on which the shoe is to be re-lasting for facilitating movement of the shoe onto the last in response to an operation of said plunger, means for holding said shoe horn stationary in said inserted position, and means for elevating the support for a last following a re-lasting operation of the plunger, thereby to effect withdrawal of the shoe horn from the re-lasting shoe and to restore the plunger for a subsequent re-lasting operation thereof.

8. In a re-lasting machine having a support for a last and a plunger biased toward a last on said support and releasably held in an inactive position against said bias; the combination therewith of means for releasing said plunger comprising a pin-carrying lever pivoted on a fixed support, a swingable arm having its free end engaged against the pin of said lever, means for moving said swingable arm bodily thereby to rock said lever, means connected with said lever whereby a said rocking, thereof releases said plunger; and means whereby said swingable arm moves out of engagement with said pin following a predetermined movement of said swingable arm.

9. A re-lasting machine comprising a support for a last, a plunger spring-biased in direction toward said support, means for releasably maintaining said plunger in an inactive position against the said spring bias, a shoe horn swingably mounted on a fixed pivot and insertible in a shoe which is to be re-lasted, means for releasing said plunger for a spring-actuated re-lasting engagement thereof with a shoe on a last mounted on said support, and means for elevating said support for restoring the plunger to its inactive position and for simultaneously withdrawing the shoe horn from the re-lasted shoe.

10. A re-lasting machine comprising a support for a last, a support for a plunger, a plunger mounted for movement in the plunger support in directions toward and from said support for a last, a relatively strong coil spring and a relatively weak coil spring both urging said plunger in direction toward the support for a last, a collar slidably mounted on the plunger between the two said springs, a finger pivotally depend-

ing from said collar and swingable by gravity into engagement with the back of a last on said support for a last, said finger having a shoulder thereon for engaging behind a strap of a shoe upper, means for releasably holding the plunger in an inactive position against the resilience of said springs, means for releasing said holding means thereby to cause a re-lasting actuation of the plunger and a simultaneous yielding movement of said finger to force said strap of upper over the rear part of the last, and means for elevating the support for a last initially compressing the lighter spring to release the finger from strap engagement and ultimately compressing the stronger spring for restoring the plunger to its inactive position.

11. A re-lasting machine comprising a support for a last, a plunger movable between an inactive position and a re-lasting position and biased toward the latter position, a latch for maintaining the plunger in its inactive position against the said bias; a latch-releasing member, a treadle, and connections between the treadle and said member whereby an initial depression of said treadle releases said latch thereby to cause a re-lasting actuation of the plunger, a second treadle in the path of movement of the first treadle whereby the second treadle is depressed by the first treadle following a predetermined initial movement of the latter, and connections between the second treadle and the support for a last whereby the said support is elevated by depression of the second treadle, thereby to restore the plunger to its inactive position following a 35 re-lasting actuation thereof.

ANGELO PERRI.
